SIGNAL SWITCHING APPARATUS

William F. Krager, Minneapolis, Kans.

Application March 15, 1940, Serial No. 324,192

3 Claims. (CL 200—59)

This invention appertains to new and useful improvements in signal switching apparatus.

The principal object of the present invention is to provide a switch for signals of the direction type which involves switch means which can be preliminarily set to operate indicating means, but which will automatically disrupt when the intended move has been executed.

Other objects and advantages of the invention will become apparent to the reader of the following specification.

In the drawing:

Figure 1 is a fragmentary top plan view showing the switch means.

Figure 2 is a section on the line 2—2 of Figure 1.

Figure 3 is a sectional view on the line 3—3 of Figure 1 showing the contactor in engaged position.

Figure 4 is a diagrammatic view disclosing the electrical connections between the electrical devices involved.

Referring to the drawing wherein like numerals designate like parts, numeral 21 denotes the automatic switch which consists of a cup-like structure 22 in which a disk 23 seats. This disk 23 is formed with a pair of openings 24—24 oversize to receive spring clip contacts 25 and 26, one or the other of which can engage a contact end portion 27 of the contactor which further includes the conductor spring 28 connecting this contactor member 27 to the binding post 29 on the bridge member 30 of insulation, which extends diametrically across the cup-like structure 22 above the bottom thereof.

An arm 31 extends from the edge of the disk 23 and overlaps the hub 32 of a steering wheel 33 which has several humps 34 provided thereon.

Obviously when, for instance, the contactor 27 is thrown to engage the clip contact 25, current will flow from the battery 35 along the conductor 36 to the contactor 27 and from there to the contact 25 and along the conductor 37 to the forward "right" lamp 14 and from there by way of the conductor 38 to the rear "right" lamp 14 and then to ground. Had the contactor 27 been thrown to the contact 26 the circuit would have been through the wire 39, front "left" lamp 13, conductor 40 and to the rear "left" lamp 13 and ground.

Obviously, when the steering wheel 33 has been moved to execute the turn, a hump 34 will actuate the arm 31 and tilt the disk 23 so that it will be moved upwardly to lift the contactor 27 out of the corresponding contact clip 25 or 26,

thus breaking the current signal circuit. The disk 23 tilts on an axis extending through the openings 24, 24.

Numerals 41 denotes the usual automobile transmission and numeral 42 represents the reverse and low gear slide. A sleeve 43 of insulation is placed on the rear end portion of this slide 42 and this is adapted to carry the contactor 44, which is capable of engaging either the contact 45 or the contact 46. The contact 45 is connected by the conductor 47 to the "Go" bulb 18 in the front signal and a conductor 48 extends from there to the corresponding lamp 18 in the rear signal 6.

15 A conductor 49 extends from the contact 46 to the "back" bulb 17 in the front signal 5 and from there the conductor 50 extends to the corresponding lamp 17 in the rear signal 6. Obviously, shifting of gears will result in energization of either the "Go" lamp or the "Back" lamps, depending upon the movement of the slide bar 42.

20 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

30 1. A signal switch, in combination with a steering member having a pair of spaced switch controlling bosses thereon comprising a case, a disk tiltably mounted in the case, one side of the case having an opening therein, an arm extending from the disk and through the opening and being disposed across the steerable member in the path of the bosses, a pair of spring clip contacts in the case, said disk having a pair of openings 35 through which the spring clip contacts project, said disk having a central opening, a flexible elongated contact member extending through the central opening and having one end anchored in the case, said elongated flexible contact being adapted to be engaged in either one 40 or the other of the spring clip contacts, said disk being adapted to be tilted by engagement of one of the bosses against the arm to dislodge the elongated flexible contact from the spring clip contact holding the same.

50 2. A signal switch, in combination with a steering member having a pair of spaced switch controlling bosses thereon comprising a case, a disk tiltably mounted in the case, one side of the case having an opening therein, an arm extending from the disk and through the opening and be-

ing disposed across the steerable member in the path of the bosses, a pair of spring clip contacts in the case, said disk having a pair of openings therein through which the spring clip contacts project, said disk having a central opening, a flexible elongated contact member extending through the central opening and having one end anchored in the case, said elongated flexible contact being adapted to be engaged in either one or the other of the spring clip contacts, said disk being adapted to be tilted by engagement of one of the bosses against the arm to dislodge the elongated flexible contact from the spring clip contact holding the same, said case having a cross member of insulation mounted therein and on which is secured the spring clip contacts and the elongated flexible contact.

3. A signal switch, in combination with a steering member having a pair of spaced switch controlling bosses thereon comprising a case, a disk 20 tiltably mounted in the case, one side of the case

having an opening therein, an arm extending from the disk and through the opening and being disposed across the steerable member in the path of the bosses, a pair of spring clip contacts in 5 the case, said disk having a pair of openings therein through which the spring clip contacts project, said disk having a central opening, a flexible elongated contact member extending through the central opening and having one end anchored in the case, said elongated flexible contact being adapted to be engaged in either one or the other of the spring clip contacts, said disk being adapted to be tilted by engagement of one of the bosses against the arm to dislodge the 10 elongated flexible contact from the spring clip contact holding the same, said elongated flexible contact having the property of springing to an upright position extending through the disk when disengaged from a spring clip contact.
